(57) **CLAIM**

We claim, the ornamental design for a keyboard for mobile communication terminal, as shown and described.

DESCRIPTION

FIG. 1 is a perspective view of a keyboard for mobile communication terminal, showing our new design;

FIG. 2 is a front elevation view thereof;

FIG. 3 is a rear elevation view thereof;

FIG. 4 is a side elevation view thereof;

FIG. 5 is a another side elevation view thereof;

FIG. 6 is a top plan view thereof;

FIG. 7 is a bottom plan view thereof; and,

FIG. 8 is another perspective view thereof, as shown in an environment including a terminal.

The broken lines illustrate portions of the keyboard for mobile communication terminal which form no part of the claimed design.
